UNITED STATES PATENT OFFICE.

HARRY A. STONE, OF NEW YORK, N. Y.

FOLDING STAND.

1,227,850.

Specification of Letters Patent.

Patented May 29, 1917.

Application filed January 7, 1914, Serial No. 810,777. Renewed October 24, 1916. Serial No. 127,500.

To all whom it may concern:

Be it known that I, HARRY A. STONE, a citizen of the United States, residing at New York, county of New York, and State 5 of New York, have invented certain new and useful Improvements in Folding Stands, of which the following is a specification.

This invention relates to folding stands.

My object is to provide improvements on 10 the folding table or stand set forth in my application filed March 28, 1913, Serial No. 757310.

The invention has for an object the elimination of certain of the so-called external 15 braces of the construction set forth in Serial No. 757310 and to provide means, preferably an improved screw clamp, for fastening together the heads of the inner or internal braces when the stand is to be extended for use.

My improvements simplify the construction, cheapen and strengthen it, and render it lighter, stronger and more durable, besides affording greater rigidity to the relatively bodily movable legs.

As with the invention set forth in my aforesaid application Serial No. 757310, the bodily movable legs enable a table top to be entirely dispensed with, as these legs 20 directly support the typewriter or other object, and the latter when thus supported, serves as a table top and brace for the said foldable, bodily movable legs.

As with the construction set forth in my 25 co-pending application Serial No. 757310, so with the present invention, I preferably couple sets of crossed internal braces, each composed of a pair of members, the pairs of braces of one set straddling those of the other set and thus these braces interbrace 30 each other. Preferably, the clamp consists of a hand-screw rotatably carried by a head to which one set of the braces is pivoted and adapted to engage screw-threads in the 35 head to which the other set of braces is connected, but I am aware that changes in construction may be resorted to in the form of the clamp, and I do not limit myself to the details of the screw clamp, except where 40 set forth in the claims.

In the accompanying drawings:

Figure 1 is a perspective looking down

on the table or stand when it is in extended condition;

Fig. 2, a side view of the table or stand 55 when folded;

Fig. 3, a detail view of the screw clamp when disconnected;

Fig. 4, a similar view showing the screw clamp as it begins to engage the head; 60

Fig. 5, a similar view, partly in section, showing the screw clamp locking the heads together; and

Fig. 6, a detail of the joint of one of the external braces. 65

The legs 1 may be of any usual or preferred construction, but are preferably made in telescopic sections, and in the nature of a tripod, but no table top is provided, and the object, such as a typewriter, is directly 70 supported on the upper ends of the legs by the insertion of the typewriter feet in the cups 2 on two of the legs and the engagement of the front of the typewriter frame by the clamp hook 3 which is pivotally mounted at 4 so that it may be readily folded, as shown in Fig. 2. When thus supported, the typewriter or other object braces the legs 1. As in the table or stand disclosed in my application Serial No. 80 757310, the legs 1 are connected by external braces 5 which are jointed or pivoted at 6 to heads 7 carried by the upper sections of the legs 1.

The braces 5 are jointed at 8 and one brace 85 section has a lip 9 which overlaps the other brace section. The braces 5 are, therefore, adapted to "break" upwardly and the lip or flange 9 holds the joint against "breaking" 90 downwardly.

In the construction set forth in my application Serial No. 757310, there are also upper braces corresponding to the lower braces 5, but in the present construction these are unnecessary, as the improved clamp shown 95 in Figs. 3, 4 and 5 causes a rigid bracing of the upper parts of the legs. I may, however, if I desire to do so, employ upper external braces similar to the lower braces 5, as provided in the table or stand set forth in my 100 application Serial No. 757310 and I do not limit myself to either dispense with or provide such braces.

The heads 7 are provided with inwardly

projecting lugs or ears 10. Pairs of upper internal, flat braces 11 are pivoted to the upper lugs or ears 10 at 12 and converge downwardly and are pivoted at 13 to the lugs or ears 14 on a head 15.

Lower braces 16 which are arranged in pairs and are straddled by the braces 11 and are in contact therewith so as to form an interbrace, are pivoted at 17 to the lower lugs 10 and at 18 to the lugs 19 of an upper head 20, the lower braces 16 thus crossing the upper braces 11 and converging upwardly, while the upper braces 11 converge downwardly.

The upper head 20 is provided with a smooth aperture or bore 21 (Fig. 5) and the lower head 15 has a screw-threaded bore or aperture 22 in alignment with the bore 21, but of larger internal diameter. Journaled in the bore 21 is the blank or cylindrical portion 23 of the clamping screw which is provided with a hand-wheel 24 which may be suitably secured thereto as by a pin 25. A shoulder 26 on the clamping screw bears against the upper face of the head 21. Below the head 21 the screw has screw-threads 27 which are larger than the bore 21 and are adapted to engage the screw-threads 22. If made larger than the bore 21, the screw-threads 27 prevent the screw from pulling out of the bore in an upward direction, while the shoulder 26 prevents pulling out in a downward direction. I do not limit myself, except where stated in the claims, to a screw-threaded part which is of greater diameter than the bore 21 as the same result could be accomplished by a collar and pin in the head 21 received in a groove in the stem 23. The tip 28 is preferably smaller and smooth to facilitate entry in the screw-threaded part 22.

When the stand is in the collapsed or folded condition shown in Fig. 2, on grasping the legs 1 and pulling them downwardly, the said legs move bodily in relation to each other and the heads 15 and 20 finally assume the position shown in Fig. 3 and afterward that shown in Fig. 4, where the tip 28 of the screw enters the screw-threaded part 22, whereupon, on turning the hand-wheel 24, the screw-threads 27 engage the screw-

threads 22 and the heads 15 and 20 are finally drawn tightly together, as shown in Fig. 5, whereupon the legs are firmly braced, the braces 5 being then in the position shown in Fig. 1 with the lip 9 overlying the said braces. The telescopic legs may be pulled out before or after the stand is opened out. The lower ends of the legs are preferably provided with suitable ball bearing casters 29.

Having thus described my invention, what I claim as new and desire to secure by Letters Patent, is:

1. In a folding stand, the combination of foldable legs, different sets of relatively movable braces for the legs, heads for the respective sets of braces, and a screw carried by one set of said heads and adapted to detachably screw into the other of said heads, whereby the braces may be rigidly connected to hold the stand extended, or, disconnected to permit folding of the legs and braces.

2. In a folding stand, the combination of foldable legs, upwardly extending braces pivoted to the legs, a head connected to said braces, downwardly extending braces pivoted to the legs, a head connected to said downwardly extending braces, the upwardly and downwardly extending braces crossing each other, and a clamp screw carried by one of said heads and adapted to detachably engage the other of said heads, whereby the braces may be rigidly connected to hold the stand extended, or, disconnected to permit folding of the legs and braces.

3. In a folding stand, the combination of foldable legs, different sets of relatively movable braces for the legs, heads for the respective sets of braces, a screw carried by one of said heads and adapted to detachably screw into the other of said heads, whereby the stand is held in extended condition when the screw is engaged with the head, or, folded when said screw is detached, and additional braces connecting the foldable legs.

In testimony whereof, I hereunto affix my signature in presence of two witnesses.

HARRY A. STONE.
